TRAFFIC SIGNAL SYSTEM

August C. Boettger, Carlstadt, N. J.

Application January 16, 1936, Serial No. 59,398

8 Claims. (Cl. 177—339)

This invention relates to signalling systems and particularly to signalling systems used to control traffic at street and road intersections.

The invention as specifically disclosed herein may be briefly outlined as follows: There is a whistle (by which I mean to include a horn or other device which is sounded by impelled air or other fluid) and means to discharge air thereto, the latter including a blower and an electric motor coupled with the rotary element of the blower. The whistle has a valve which when opened allows the discharged air to blow the whistle, and this valve has electro-magnetic control means. An electric circuit for the motor and such control means is provided, and this has a circuit-closer by which the police officer or other attendant can put in action the motor and blower and energize the control means for the opening of the valve, the consequent whistle blast being continuously sounded so long as the circuit-closer is maintained closed; for the circuit there is also circuit-closing means by which the officer, wishing to give a peremptory signal, may cause a long blast followed by short blasts or intermittent blasting to be sounded.

It will usually be desired to provide for varying the intensity of the whistle blasts at times (for instance, reducing it at night or in the vicinity of a hospital) wherefore the invention also contemplates means for varying the intensity of the air-discharge. This means is also electrically operated by the manual actuation of a single circuit-closer, and associated with it are electrically actuated tell-tales to indicate the "loud" or "soft" sounding state of said means.

In the drawings—

Fig. 1 is a front general elevation of the mechanism with the front wall of the major housing removed;

Fig. 2 is a similar elevation on a larger scale of the whistle housing, whistle and other parts, the whistle appearing partly in section;

Fig. 3 is a side elevation, as seen from the right, of what is shown in Fig. 2;

Fig. 4 is a side elevation of the intake tube, damper solenoid and its associated mechanism, the casing 21 appearing in section;

Fig. 5 is a left side elevation of what is shown in Fig. 4;

Fig. 6 is a plan and Fig. 7 a side elevation of a certain reversing switch device;

Fig. 8 is a side elevation on a larger scale of mechanism within one of the housings of such device;

Fig. 9 is a front elevation of the cam and

means for rotating the same, and Fig. 10 is a similar view of what is shown in Fig. 9 with the front plate of the frame of this part of the mechanism removed;

Fig. 11 is a diagram of the circuit connections; 5 and

Fig. 12 is a plan of the main crank.

The mechanism is in part contained in a major housing 1 and in part in a minor housing 2 surmounting the major housing. The major 10 housing contains the actuated mechanism and the minor housing the control mechanism.

In the major housing is an electric motor 3 which drives a rotary blower 4 whose intake is a tube 5 having an oscillatory damper 6 and which 15 blower discharges into a whistle 7 contained in a case 8 which is open to the atmosphere through a louvered opening 9 in a side wall of the housing 1.

The whistle is formed generally like a police 20 whistle but is slotted at the top forward of its air-outlet slot 1a and receives therein a slide valve 10 pivoted to one arm of a lever 11 fulcrumed in the case 8 and whose other arm (exterior of the case) is formed partially as a counterbalance 25 weight 11a and has projecting from it past the fulcrum an elastic blade 11b preferably equipped with a felt or other soft pad 11c. A solenoid 12 is attached to the outside of the case and its armature 13 has a pin 13a. A lever 14, fulcrumed between its ends on the solenoid frame and reaching from the case, has its outer arm overhanging this pin and its inner arm connected to a link 15 whose upper end is slotted and receives in its slot the reduced end of the 30 weight 11a. Such reduced end is received in the notch 16a (padded top and bottom with felt) of a block 16 affixed to the case and which is wide enough to permit some oscillation of lever 11 and consequent reciprocation of the 35 whistle valve. A spring 17 normally acts to hold lever 14 in the position of Fig. 3, or with the link holding the reduced end of lever 11 against the top of the notch, in which position lever 11 is held stationary (valve 11 closed) by lever 14 40 acting through the link. But if, the solenoid being energized, the armature 13 is elevated until its enlarged lower end is held near the solenoid frame, said armature will act through parts 14, 18 and 11 to hold the valve in open position; 45 nevertheless, with the armature so held elevated and tending thus to hold the valve in open position the lever 11 will still be free to be moved to close the valve (due to the slot in link 15) by pressure applied to its blade 11b, as by an actua- 50

55

tor 72 to be described. In short, in the normal or illustrated positions of the parts (the armature down), spring 17 acts through lever 14, the link and lever 11 to hold the whistle valve in closed position. When the solenoid is energized the lever 14 and link are moved to release lever 11, whereupon spring 18 acts through said lever to hold the whistle valve open; but if in that state of the parts the blade portion 11b of lever 11 is 10 pressed the valve will be closed—as will appear, this pressing occurs intermittently and so will cause intermittent blasting of the whistle. (The position of the valve in Fig. 2 is taken as its closed position, since it then cuts off such flow of air to the air-outlet 7a as will cause whistling.)

Any suitable support 19 affixed to the intake tube 5 has attached thereto a solenoid 20 and a casing 21 for mechanism, actuated by the armature 22 of the solenoid, for determining the position of the damper 6. This armature has a depending rack 23 which is normally held by gravity acting on the armature against a vertically adjustable screw-stop 24 supported in a depending bracket 21a of the casing. A shaft 25, journaled 20 in the casing and having a pinion 26 meshing with the rack, is normally urged in the anti-clockwise direction (Fig. 4) by the weight of the armature and a helical spring 27 coiled about the shaft and connected to a collar 25a thereon and to the casing. The shaft has affixed thereto a ratchet 28. This is engaged by a spring-pressed pawl 29 on a disk 30 which forms a unit, rotative on the shaft, with a cam 31 and a ratchet 32, this ratchet being engaged by a spring-pressed pawl 33 on the casing. The teeth of ratchet 28 face clockwise so that when the armature rises the engagement of the ratchet with its pawl causes said unit to turn clockwise; when said armature is allowed to fall (pawl 29 clicking idly over ratchet 28) the other ratchet and pawl prevent counter-clockwise rotation of said unit. The throw of the armature is such only as to turn the shaft a half-revolution. But, since the impulse imparted to the armature by the solenoid is sudden, said unit tends to overrun, or rotate more than a half-revolution. To prevent this there is a fin 34 on the rack adapted when it rises to be engaged by a stop-pin 35 on the disk 30. The damper has an arm 36 held bearing against the cam by a spring 6a connecting the damper shaft with the intake tube. On every other upstroke of the armature the cam is turned to the position shown in Fig. 4, where it has permitted said arm to rise and the damper to be fully open; on the remaining upstrokes of the armature the cam is turned 180° from the position shown so that it depresses said arm and the damper is in about the position x in Fig. 4. In the first position of the damper the blast is mild, for soft whistle blasting; in the second position the blast is strong, for loud whistle blasting.

On the housing 2 is a frame 37 to the back plate of which is secured an insulating block 38 having a fixed contact 39 and an elastic yielding contact forming a circuit-closer a which as to its end shown hook-shaped may engage or disengage contact 39. There is a rotary member, comprising a shaft 41 journaled in said frame, a segment 42 and a hook 43 (the segment and hook being fixed to the shaft) and an insulating block 44 carried by the segment which, under the influence of a spring 45 connecting said member with the frame, holds said member (specifically the segment) normally against a stop 46 and 75 hence block 44 in the position to maintain circuit-

closer a open and thus provide a break in the circuit. A crank 47 (normally urged clockwise by a spring 48 connecting it with some fixed point) having a stud 47a to engage the hook 43, affords manual means to turn said member 5 counter-clockwise until the segment engages a stop 49, upon which, if the handle is released, it will be returned by spring 48 while (as will now appear) said member returns under the influence of spring 45 more slowly, or subject to means 10 which opposes the action of the spring 45 to return it quickly. Meshing with the segment is a pinion 50 formed as a unit with a gear 51, and this gear meshes with a pinion 52 formed as a unit with a one-tooth ratchet 53, the spring 45, 15 said member and the gearing to and inclusive of this ratchet forming the driving train. The ratchet is engaged by a spring-pressed pawl 54 mounted on a gear 55 which is concentric with but free to rotate independently of the unit 52—53 20 and which meshes with a pinion 56 formed as a unit with the ratchet 57 which coacts with an escapement pawl 58, such pawl and this gearing forming the driven train. When said member is manually turned counterclockwise (arrows, Fig. 25 10) circuit-closer a closes, the spring 45 is put under tension and the gearing to and inclusive of the ratchet 53 is rotated relatively to the remainder of the gearing, the pawl 54 clocking idly over said ratchet. When, as by releasing the crank, 30 said member is released the driving train rotates and rotates the driven train but subject to the resistance afforded by the vibrating escapement pawl 58. When the driving train is made to drive the driven train there is driven as 35 a part of the latter a cam 59 (controlling a circuit closer f to be referred to) which is a unit with the gear 55 and has a series of equally spaced peripheral humps. In short, the function of the driving train is to drive this cam, the remainder 40 of the driven train being means merely, as stated, to oppose fast rotation of the cam although the operator frees the crank to permit it to return under tension of its spring 43.

Fixed in the housing 2 in any way (not shown) 45 are a plate 60 and a pair of casings 61. On bosses 60a of the plate is fulcrumed a lever device or lever 62 which (as will appear) is normally held in the position of Fig. 6 but may be manually moved to the position of Fig. 7 in which its circuit closer b engages a contact 60b of the plate. Each casing contains well-known circuit making and breaking means as follows: There is a cable 63 extending from the lever 62 through the corresponding boss and having a link 64 connected therewith, the link having a stud 64a. This stud engages a notch in the end of a toggle-lever 65 having upper and lower hooks respectively engageable with the upper and lower edges 66a of a metal box 66 which is affixed to an insulating plate 67 which is itself suitably affixed in the casing. This toggle-lever has its outer end connected by a spring 68 with a fulcrumed circuit-closer c which is fulcrumed on the box at 69 (being insulated therefrom at 70) and which 65 forms a contact to engage the contact 71 on the base. When the cable is pulled the toggle-lever shifts on its then fulcrum at one of the edges 66a until the spring passes the dead-center relation to the fulcrum 69, whereupon the toggle 70 lever and circuit-closer c spring to their opposite positions; hence alternate pulls on the cable cause engagement and the remaining pulls disengagement of the circuit-closer c with contact 71. The two cables are connected to the lever 75

62 and the springs hold the latter in its normal position (Fig. 6). On assembly of the casings and their contents with the plate 60 and lever 62 one of the circuit-closers is put in open and the other in closed position, wherefore on each operation thereafter of lever 62 they will reverse their positions.

72 is a relay whose armature 73 is normally held up by a spring 74 active on a plunger 75

10 which may exert depressing influence on blade 11b of lever 11 to hold the whistle valve 10 closed.

At d (Figs. 1 and 11) is a circuit-closer to connect the system with service lines. At e and f are normally open circuit-closers to be referred

15 to, the latter having a lug f'.

The main circuit comprises a lead 76 (containing a condenser 77) which includes the motor 3 and is then branched, one branch 76a having the circuit-closer e and the other 76b the circuit-closer a. There is a shunt 78 around the motor and including the whistle-valve-controlling solenoid 12. There is another shunt 79 around shunt 78 and containing relay 72 and adapted to be connected with branch 76b by the circuit-closer f.

20 25 There is a shunt 80 which includes the damper-controlling solenoid 20 and is adapted to be closed by the circuit-closer b and is connected (beyond such circuit-closer relatively to the solenoid) to the unbranched portion of the main lead

30 35 by branches 80a and 80b respectively having the circuit-closers c, said branches also containing, respectively, tell-tales, as lamps, L (for loud) and S (for soft).

The operation (excluding that of the damper for the meanwhile) is as follows, assuming d to be closed:

The normal position of parts 10—11, which I term the air-flow controller, is closed, i. e., the actuator formed by solenoid 12 is de-energized

40 45 and spring 17 is acting through lever 14 and link 15 to hold the controller in the position of Fig. 2.

If said actuator be energized by the closing of e or a the means 14—15, being retracted by armature 13, shifts to the position to free the controller and actually acts through spring 18 to hold the controller yieldingly in open position. If, in this condition of the controller, the relay 72 be energized its plunger 75 (which, in effect, is an extension of its armature) will press down on the blade 11b of the controller and so move the same to closed position against the tension of spring 18.

50 55 Suppose the attendant wishes to sound the whistle non-intermittently, or by a single relatively long blast. He closes e, wherefore the motor and blower will be driven and the actuator energized and the blast will be sounded as long as e remains closed.

If he wishes to signal peremptorily he pulls

60 65 down crank 47 to store up energy in spring 45 and on release of the crank cause rotation of the cam or interrupter 59. The downward movement of the crank involves the closing of a (which remains closed until, the crank being released, the

65 segment 42 reassumes its rest position against stop 46), so that the motor and blower are driven and the actuator energized to cause the controller to be held yieldingly (by spring 18) in open position.

In view of this condition of the controller

70 75 there will be a continuous blast of the whistle during the downstroke of the crank and so long as it is held against return. When the crank is released the cam or interrupter 59 is rotated so that its humps successively engage lug f' of circuit-closer f to close the latter, and on each such

closing, the actuator formed by relay 72 being thus energized, plunger 75 depresses the controller to closed position against the tension of spring 18, wherefore during the rotation of the interrupter the reciprocated controller causes intermittent blasting of the whistle. In other words, the pulling down of the crank followed by its release effects sounding of the whistle in one long blast followed by a series of short blasts. Of course, when the rotation is checked by segment 10 15 20 25 30 35 40 45 50 55 60 65 70 75 80 85 90 95 100 105 110 115 120 125 130 135 140 145 150 155 160 165 170 175 180 185 190 195 200 205 210 215 - for the whistle, an electro-magnetic actuator, means, including an armature for the actuator, to hold the controller in one of said positions when the armature is at one of its limits determined by the energized or de-energized state of the actuator, said controller being yieldingly urged to the other position when said means moves to a position in which the armature is at its other limit, a second electro-magnetic actuator 10 having its armature, when the second actuator is energized, adapted to move said controller to the first position, circuit-forming means having a portion formed with a break therein and including the first actuator and a normally open portion including the second actuator, means to close or open the break in the first circuit-portion, and means to close the second circuit-portion while the break is closed.

5. Signal mechanism comprising a whistle, a fluid-flow controller movable to either of two positions in one of which it is in and in the other of which it is out of the path of actuating fluid for the whistle, an electro-magnetic actuator, means, including an armature for the actuator, to hold the controller in one of said positions when the armature is at one of its limits determined by the energized or de-energized state of the actuator, said controller being yieldingly urged to the other position when said means moves to a position in which the armature is at its other limit, a second electro-magnetic actuator having its armature, when the second actuator is energized, adapted to move said controller to the first position, circuit-forming means having a portion formed with a break therein and including the first-actuator and a normally open portion including the second actuator, a circuit-closer for the break normally urged to move to closed position, means holding said circuit-closer in open position and movable therefrom to release the same and back, and means, actuated by the last-named means upon such movement thereof, to close the second circuit-portion while the break is closed.

6. Signal mechanism comprising a whistle, a fluid-flow controller movable to either of two positions in one of which it is in and in the other of which it is out of the path of actuating fluid for the whistle, an electro-magnetic actuator, means, including an armature for the actuator, to hold the controller in one of said positions when the armature is at one of its limits determined by the energized or de-energized state of the actuator, said controller being yieldingly urged to the other position when said means moves to a position in which the armature is at its other limit, a second electro-magnetic actuator having its armature, when the second actuator is energized, adapted to move said controller to the first position, circuit-forming means having a portion formed with a break therein and including the first-actuator and a normally open portion including the second actuator, a circuit-closer for the break normally urged to move to closed position

tion, means holding said circuit-closer in open position and movable therefrom to release the same and back, and means, actuated by the last-named means upon such movement thereof, to close the second circuit-portion.

7. Signal mechanism comprising a whistle, a fluid-flow controller movable to either of two positions in one of which it is in and in the other of which it is out of the path of actuating fluid for the whistle, an electro-magnetic actuator, means, including an armature for the actuator, to hold the controller in one of said positions when the armature is at one of its limits determined by the energized or de-energized state of the actuator, said controller being yieldingly urged to the other position when said means moves to a position in which the armature is at its other limit, a second electro-magnetic actuator having its armature, when the second actuator is energized, adapted to move said controller to the first position, circuit-forming means having a portion formed with a break therein and including the first-actuator and a normally open portion including the second actuator, a circuit-closer for the break normally urged to move to closed position, means holding said circuit-closer in open position and movable therefrom to release the same and back, and means, actuated by the last-named means upon such backward movement thereof, to alternately open and close the second circuit-portion while the break is closed.

8. Signal mechanism comprising a whistle, a fluid-flow controller movable to either of two positions in one of which it is in and in the other of which it is out of the path of actuating fluid for the whistle, an electro-magnetic actuator, means, including an armature for the actuator, to hold the controller in one of said positions when the armature is at one of its limits determined by the energized or de-energized state of the actuator, said controller being yieldingly urged to the other position when said means moves to a position in which the armature is at its other limit, a second electro-magnetic actuator having its armature, when the second actuator is energized, adapted to move said controller to the first position, circuit-forming means having a portion formed with a break therein and including the first-actuator and a normally open portion including the second actuator, a circuit-closer for the break normally urged to move to closed position, geared means holding said circuit-closer in open position and movable therefrom and normally urged to move back, a normally open circuit-closer for the second circuit-portion, and an interrupter to be clutched and moved by said gearing means when the latter moves back and having a series of humps to move the circuit-closer repeatedly to closed position.

AUGUST C. BOETTGER. 60
